CLAIM

The ornamental design for a sample collection device as shown and described.

DESCRIPTION

FIG. 1 is a perspective view of a sample collection device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of a portion thereof.

The evenly spaced broken lines in the drawings depict portions of the sample collection device that form no part of

(Continued)

the claimed design. The dot-dash broken lines depict the bounds of the enlarged views and form no part of the claimed design.

1 Claim, 4 Drawing Sheets
